UNITED STATES PATENT OFFICE.

FRED B. KING, OF TOLEDO, OHIO, ASSIGNOR, BY MESNE ASSIGNMENTS, TO THE WILLYS-
OVERLAND COMPANY, OF TOLEDO, OHIO, A CORPORATION OF OHIO.

SEAT STRUCTURE.

Application filed October 3, 1919. Serial No. 328,116.

To all whom it may concern:

Be it known that I, FRED B. KING, residing at Toledo, county of Lucas, and State of Ohio; have invented certain new and useful

5 Improvements in Seat Structures, of which I declare the following to be a full, clear, and exact description.

This invention relates to an improved seat construction, such as is particularly adapted 10 to be employed in connection with vehicle seats, especially of the form commonly used in automobiles and vehicles of like character.

One object of the invention is to provide 15 a seat construction of this character which is of simple construction and efficient in operation.

A further object of the invention is to provide an improved form of border frame 20 for supporting the seat and maintaining the form of same against distortion.

A further object of the invention is to provide a border frame provided with improved means whereby the canvas forming 25 a cover for the springs may be readily secured to the border frame to retain the frame in proper position.

Further objects of the invention relate to economies of manufacture and details of 30 construction as will appear from the detailed description to follow.

The objects of the invention are accomplished in one instance by the devices and means described in the following specification, but it is evident that the same may 35 be varied widely without departing from the scope of the invention as pointed out in the appended claims. A structure constituting one embodiment of the invention 40 is illustrated in the accompanying drawings forming a part hereof in which:

Figure I is a top plan view, partially broken away, of a seat construction embodying the novel features of the present 45 invention.

Figure II is an end view, partially in section, as indicated by the line II-II of Fig. I, and illustrating the relative position 50 of the various elements of the seat structure with respect to each other.

Figure III is a perspective view of a portion of the border frame illustrating the manner of securing the canvas layer thereto.

Figure IV is a top plan view of the border 55 frame.

Figure V is a transverse sectional view, taken along the line V-V of Figure IV, and illustrating the particular form of the members which make up the border frame.

In one embodiment of the invention illustrated herewith, 1 indicates a seat support comprising a lower border frame 2, the general outline of which is substantially the same as that of the completed seat, and which supports a suitable form of wire mesh 3, firmly secured to the border frame in any suitable manner. A plurality of coiled springs 4, each of which is preferably enclosed within a pocket 5 formed of canvas or other suitable material, rest upon and are supported by the seat support previously described. A layer of canvas or other suitable fabric material 6 encloses the coiled springs previously described and the upper border frame 7, is preferably positioned 75 upon the upper end portions of the coiled springs previously described and enclosed by the fabric covering 6. The upper border frame 7 comprises two members 8 and 9, the member 8 being so formed as to extend 80 along the ends and one side of the seat while the member 9 preferably extends only along one side of the seat. The members 8 and 9 are firmly secured to each other at the opposite ends thereof thus forming a 85 border frame which is of substantially rectangular form and of sufficient stiffness to give form to the seat cushion and prevent distortion of the same. The member 8 of the border frame is preferably formed of wire of such size as to offer sufficient resistance to the accidental bending or distortion of the rear and side portions of the cushion, while the member 9 is formed of flattened material provided with a bead 10 90 formed therein, this construction offering considerable resistance to the bending inwardly of the front edge portion of the cushion which is the part of the cushion structure most liable to be subjected to 95 blows. The flattened strip 9 is provided with a plurality of spaced openings 11 formed therein and preferably located adjacent the bead 10 whereby means is provided for suitably securing the canvas or fabric 100 layer 6 to the front edge portion of the border frame by means of a suitable thread or cord 12. The thread or cord 12 is preferably passed through the fabric or canvas layer 6 and through the spaced openings 105 110

11 formed in the member 9 of the border frame in the manner illustrated in Fig. III of the drawing. It will be noted that the form of border frame illustrated herewith is capable of being constructed at a minimum cost, and at the same time the parts are so arranged as to provide a suitable support for the ends and rear portions of the seat cushions while at the same time a more rigid member is provided for giving form to the front edge portion of the seat cushion which is adapted to withstand any blows or strains to which the front edge portion of the cushioning may be subjected and whereby the front edge of the cushion is maintained in suitable position and supported against distortion. It will be seen that the member 9 of the border frame is constructed so as to permit a slight degree of bending in a vertical direction, while at the same time preventing any substantial inward bending of the front edge portion of the border frame in a horizontal direction.

25 The seat cushion which may be of any suitable or desirable construction is positioned above and rests upon the fabric or canvas material 6 which forms an enclosure for the coiled springs. A form of cushion which may be employed comprises a lower layer of coarse fabric such as burlap indicated at 13, a layer of filler material 14 positioned thereabove, and a layer 15 of canvas positioned upon the filler material and in turn supporting a layer of cotton or other soft filler material 16 upon which the upholstery cover 17 is adapted to rest. The elements 13 to 17 inclusive described above go to make up the form of seat cushion which has been found to be suitable for use in connection with seat structures of this character. A bead 18 is formed in the fabric forming the outer cover of the seat cushion, and a strip of similar material 19 forming an apron extends downwardly from the bead 18 and the lower edge portion of the apron 19 is suitably secured to the border frame 2 as illustrated in Fig. II of the drawings.

50 It will be evident from the above description that an efficient and economical form of border frame is provided which when assembled into position with respect to the other elements comprising the seat structure serves to support the outer edges of the cushion and give form to the same. As it has been found to be desirable to construct that portion of the border frame positioned along the front edge of the cushion of material which is less readily bendable than the other portions of the border frame since the front edge portion of the cushion is more exposed to strains and blows liable to distort the same. The forming of the border frame in two parts provides a ready means for thus form-

ing the front portion of the frame of less bendable material while at the same time the other portions of the frame can be formed of a wire as is usual in frames of this character. As the flattened portion of the member 9 of the border frame is positioned substantially horizontally relative to the seat structure, this member is capable of being bent to a certain extent in a downward direction while at the same time it offers sufficient resistance to a bending stress in a horizontal direction.

While I have shown and described in considerable detail a specific embodiment of my invention, it is to be understood that this showing and description is illustrative only and for the purpose of rendering my invention more clear, and that I do not regard the invention as limited to the precise details of construction illustrated or described except in so far as I have included such limitations within the terms of the following claims, in which it is my intention to claim all novelty inherent in my invention broadly as well as specifically.

What I claim as new and desire to secure by Letters Patent is:

1. In a spring seat structure having a plurality of coil springs and a cushion supported thereby, a border frame for said seat comprising a wire bent to extend across the back and the two ends of said seat and a flat metal strip extending across the front of said seat, said strip having its ends secured to the ends of said wire and having a bead formed thereon at its front edge, thereby increasing its stiffness and providing a rounded edge substantially throughout its length to engage an upholstery covering.

2. In a spring seat structure an upper border frame comprising a strip having a down-turned flange and a bent wire forming the other three sides of the frame; a layer of fabric overlying said border frame and extending down therefrom to form an apron, said flange serving to stiffen the strip and to provide a rounded edge over which said fabric passes.

3. In a spring seat structure an upper border frame comprising a metal strip and a three-sided frame member having its end connected with said strip, a layer of fabric overlying said border frame and extending down to form an apron, and means for securing said fabric to said strip, said strip having its outer edge formed with a stiffening bead for the greater portion of its length and said fabric passing over the rounded edge of said bead.

4. In a spring seat structure, an upper border frame comprising a metal strip, a layer of fabric overlying said border frame and passing over the edge of said strip and down to form an apron, and stitching to hold said fabric to said strip, the edge of said

strip being bent laterally to stiffen the same and to form a curved bearing face substantially throughout its length for said fabric.

5. In a spring seat structure, a base, a plurality of coil springs carried thereby, a fabric cover for said base and springs, an upper border frame comprising a wire extending across the back and the two ends of said seat, and a metal strip forming the front

of the frame and having its ends secured to the ends of said wire, said strip having its outer edge flanged to form a bead to stiffen the same and to provide a smooth seat for said fabric and its inner edge flattened and resting upon the springs.

15 In testimony whereof, I affix my signature.

FRED B. KING.
